UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF MICHIGAN.

TOY MACHINE GUN.

Application filed August 29, 1927. Serial No. 216,068.

My invention relates to toy machine guns and a special object of my improvements is to perfect the operation of the device embodied in my application filed in the United States 5 Patent Office November 29, 1926 and having the Serial Number 151,309, and to improve the construction of the same.

I accomplish this object in the apparatus shown in the accompanying drawings, in 10 which:

Figure 1 is a side elevation of a toy machine gun embodying my invention, the standards being broken away.

Figure 2 is an end elevation looking from 15 the right of Figure 1.

Figure 3 is an inverted plan view, a part of the barrel and crank being broken away and the base plate removed.

Figure 4 is a vertical section through the 20 axis of the barrel.

Figure 5 is a section on the line V, V, Figure 4.

Figure 6 is a section on the line VI, VI, Figure 4.

25 Figure 7 is a perspective view of the three parts forming the casing and operating part therein, arranged in the relative position they take when being assembled.

a is the casing and b the operating cam 30 therein. d is the barrel having the enlargement d² at its outer end for constraining the movement of the cork h.

e is the spring for projecting the air compressing piston f² on the end of the retracting 35 rod f.

g is the connecting-rod running parallel to the barrel d beneath the same and turned upward through a slot in the barrel-part d² and formed into a loop g² therein for engaging the 40 cork h.

In my said previous application the rod g was rigidly connected to the retracting means. It is impracticable to obtain corks of precisely the same size and with the cork-actuating part 45 g² traveling an invariable distance the placing of the cork thereby in the muzzle of the barrel d was not as uniform as the perfect action of this apparatus required. I have, therefore, provided a yielding connection between the 50 retracting means and the cork-actuating part so that the cork is now forced to position in the muzzle of the gun with a practically uniform force whatever the casual variation in the size of the cork may be and I have pro-

vided this improvement without extra expense and even with a reduction in the cost of manufacturing, in the following way.

g² is a longitudinal slot in the lower wall of the barrel d back of that portion traversed by the piston f². The rod g is turned upward at 60 its rear end and extends in a portion d³ through the slot g² and between the sixth or seventh coil of the spring e. Said rod then turns again at right angles and extends in a part g⁴ parallel to the axis of the spring e for 65 a distance sufficient to hold the rod in the coils of said spring.

This not only perfects the action of the apparatus but provides for the convenient assembling of the parts.

As further contributing to the facility of assembling the constituent parts I provide a single stamping which forms the casing and barrel-frame, and secures the barrel and shaft of the actuating-cam in position.

a indicates the casing as a whole. This is made up of two semi-cylindrical portions, a², a², united at their upper ends and provided at their adjacent edges with apertures a⁴, a⁵, which register and form the bearings for the 80 cam-shaft b². ac, indicates lugs extending from the lower edges of the parts a², a² and aca indicates similar lugs similarly extending from the lower edges of said part and located close to the rear-vertical edges of said parts 85 (Figs. 5 and 7c).

c is the base plate consisting of a stamping of sheet metal having the sockets, c², c², c² for receiving the upper ends of the adjustable standards, having its periphery turned down 90 in a strengthening-flange and provided with apertures c³ for receiving the lugs ac and a single aperture c³a for receiving the lugs aca, aca.

The method of assembling these parts is 95 illustrated in Figure 7 in which (c) shows the stamping for the casing inverted and (b) shows the cam and cam-shaft in position to be placed into engagement with the stamping of the casing and (a) shows the inverted base 100 plate ready to be put in position.

These parts are assembled by bringing the shaft b² opposite the apertures a⁴, a⁵ and then closing the parts a², a² together so as to engage said shaft in said apertures. The base plate 105 c is then brought down upon the semi-circular edges of the parts a², a² with the lugs ac extending through the apertures c³ and the

lugs $a_3 a$ extending through the aperture $c^3 a$. Said lugs are then turned over, as shown in Figure 4, binding the parts together.

a^6 is a lateral extension of the portion of the 5 casing-stamping joining the parts a^2 , a^2 , which extended portion when bent together forms the barrel-frame. This is secured in position by a tongue a^7 engaging the adjacent 10 edges of the parts a^6 to hold the same in position. The barrel is inserted in the barrel-frame, as shown in Figure 4, and a lug ad extending from the casing-stamping is bent over the end edge of the barrel to secure it in position.

15 An aperture α may be formed in the casing-stamping and the part of the barrel de that is bent downward to form a stop for the spring e may engage in said aperture.

What I claim is:

20 1. In an apparatus of the kind described, a stamping having two complementary parts adapted to be bent to bring the edges of said parts together to form a casing and having registering apertures in said edges, a part 25 of each of said apertures being in one edge

and the other part in the other edge, and an operating part having a shaft, said shaft being engaged by the registering parts of said apertures, a base plate having apertures 30 therein, and lugs extending from the other edges of said parts and engaging in the apertures in said base plate.

2. In an apparatus of the kind described, a barrel, a stamping having two complementary parts united by a portion adapted to be 35 bent around said barrel throughout the width of said portion to bring the edges of said parts together to form a casing and having registering apertures in said edges, a part of each of said apertures being in one edge and the other part in the other edge, and an operating part having a shaft, said shaft being engaged by the registering parts of said apertures, and means for holding said parts in their bent 40 position, said stamping being provided with a lug ad adapted to engage over the end edge of the barrel.

In testimony whereof, I sign this specification.

WILLIAM F. SCHMIDT.
